AUTOMATIC SAMPLER FOR LIQUID
HYDROCARBON STREAMS

William N. Kestner, Walter C. Kohfeldt, and
Lowrie C. Barillier, Baton Rouge, La., assignors
to Standard Oil Development Company, a cor-
poration of Delaware

Application May 26, 1951, Serial No. 228,502

2 Claims. (Cl. 73—422)

1

The present invention relates to an apparatus or system for collecting liquids for the purpose of subsequently analyzing the collected samples.

The quality of the fluids obtained in the commercial production of many liquids will vary greatly during different periods of their manufacture, although the production rate may be nearly constant. It will be appreciated therefore, that a sample of a liquid taken at one step or stage of its manufacture would not be truly representative of the quality throughout the entire period of production or flow of such liquid, from the source at which it is being manufactured. At one period of its manufacture it may be very rich, at another period very lean.

An object of the present invention is to provide a simple, inexpensive means for the collection of a representative sample of liquid flowing through a line over a period of time.

Another object of this invention is to provide means for collecting a liquid sample at the existing pressure in the line through which the liquid is flowing.

A still further object of this invention is to provide a liquid sampling device in which the sampled liquid does not pass through the sampling device, reducing explosion hazard when explosive liquids are being handled.

To the accomplishment of the foregoing and related ends, the invention, then comprises the features hereinafter fully described, and particularly pointed out in the claims, the following description and the annexed drawing setting forth in detail certain illustrative embodiments of the invention, these being indicative, however, of but a few of the various ways in which the principle of the invention may be employed.

Referring now to the drawing, 1 represents the main line through which the liquid medium to be sampled flows. Connected to this line through line 2 is a sample chamber 3. A line 4, provided with pressure regulators 5 connects chamber 3 with motor valves 6 and 7, such as conventional diaphragm operated motor valves. The actual valve mechanisms 8 may be of a needle valve type or any other type adapted for use in small size (small diameter) equipment. The motor portions 9 may be of any suitable design such as the standard flexible diaphragm motor operated by fluid pressure, as air pressure. The flexible diaphragms 10 are attached in conventional manner to valve stems and accordingly the needle closure portions 8 are opened or closed. These valves may be spring loaded, as by springs 12. As shown in the drawing, each

2

spring 12 serves as a tension spring and is so adjusted as to hold the valve needle in a normally closed position. Upon application of instrument air pressure to the under side of the diaphragms, the valve stems 11 are raised to open the valves to the flow of fluid, the springs 12 being accordingly subjected to somewhat greater tensions. When the instrument air pressure is released, the normal tension of the springs moves the valve needles into their normally closed position.

Motor valves 6 and 7 are connected by line 13. Lines 14 and 15 connect motor valve 7 with collecting pot 16. Collecting pot 16 is provided with vent line 17 and sample chamber 3 is provided with vent line 18 (normally closed).

A timing apparatus 19 such as a time cycle controller is shown as a means for controlling the several motor valves according to predetermined time intervals. While this time cycle controller may be any type or kind of controller desired, it is obviously only necessary that it be capable of performing the desired operations in a satisfactory manner. By this, we mean that the controller may be electrically operated or it may be operated by a spring operated clock mechanism.

Time cycle controllers operate according to pins, placed in holes around the circumference of a rotating plate. Thus by inserting pins into these holes over certain time intervals said pins, upon rotation of the plate, cooperate with other mechanism of the controller to permit flow of "instrument air" to such control apparatus as the air operated motor valves 6 and 7. Such time cycle controllers are standard industrial equipment and may be purchased from equipment dealers or directly from instrument manufacturers.

Instrument air from an air supply, not shown, comes by way of a line 20 and passes through an air pressure reducer or regulator 21 to reduce the air pressure to that required for operation of such motor valves. This regulator 21 also contains a strainer element for elimination of foreign material from the air previous to entrance into the cycle controller. Said cycle controller contains valves for transmitting air pressure from the inlet air line 20 to air control lines 22 and 23 and for closing off and exhausting air pressure from said lines 22 and 23.

As shown in the drawing, these several air service lines transmit air pressure to the under side of the motor valve diaphragm members 10 so that an increase of instrument air pressure on the underside of said diaphragms will operate to raise

the diaphragms and accordingly open the valves to the flow of fluid displaced by the liquid to be sampled. Springs 12 are so adjusted in tension that upon release of air pressure on the diaphragms the several valves will be positively closed. It is not critical that said air pressure be transmitted to the under side of these diaphragms for opening the valves since it may be piped to the upper side of the diaphragms and operate to close the valves by compression of the spring 12.

Connected to line 13 by means of line 24 is a mercury pot 25. A manometer tube 26 provided with capillary 27 is connected by flexible line 28 to mercury pot 25. A fritted glass disk 29 pervious to air but impervious to mercury is fitted in the upper part of tube 26 below capillary 27. By fixing the volume of mercury displaced, a constant sample withdrawal rate is insured. A calibration mark 30 is made on the lower part of tube 26. A clamp 31 fitted with screw adjustment is provided at an upper portion of tube 26 to adjust elevation thereof to bring the mercury level therein exactly to calibration mark 30.

In order to adapt the apparatus for the collection of liquid, the vessel 3 is first filled with a displacement liquid such as water and vessel 25 with mercury.

In the operation of this invention instrument air from line 20 passes through cycle controller 19, air line 23 to the under side of diaphragm 10 in motor valve 6. Air pressure at this point opens the valve needle 8 against the tension of spring 12. Under these conditions liquid to be sampled flows from line 4 to vessel 3 and displaced liquid flows through line 4 through valve 6 and lines 13 and 24 into vessel 25 displacing mercury into manometer tube 26 to fritted disk 29. The control clock 19 holds valve 6 open for such a predetermined time as is desired, valve 7 remaining closed. At the end of this time the cycle clock 40 operates to permit closing of valve 6 and shortly after the opening of valve 7. As soon as this is accomplished the mercury in tube 26 forces the water out of vessel 25 through valve 7 into vessel 16 where it is measured. The volume of water in vessel 16 then represents the volumes of the sample in vessel 3.

It is clear from the above description that simple, inexpensive device has been provided for the collection of liquid samples at the existing line 50 pressure without danger of explosion in case inflammable liquids are being handled. Furthermore, the functioning of the sample can be visually inspected throughout the entire operation merely by observing the mercury in the glass manometer tube assembly. By providing a large number of interchangeable manometer tubes

flexibility in both size of total sample collected and period of sampling can be obtained. Furthermore, a single timing device can be used to actuate valves of several sample assemblies, thus assuring the collection of several composite samples simultaneously.

The nature and objects of the present invention having been thus described and illustrated, what is claimed as new and useful and is desired to be secured by Letters Patent is:

1. A liquid sampling system comprising in combination, a sample container adapted initially to receive a body of sealing liquid displaceable by the sample as collected, a sample inlet conduit opening into said container, a collector vessel for collecting displaced sealing liquid from said sample container, a transfer conduit connection between said container outlet and the collector vessel, an auxiliary receiver for displaced sealing liquid intermediate said container and the vessel for displaced sealing liquid, said auxiliary receiver having one side directly connected into said transfer conduit, a first motor valve in said transfer conduit disposed upstream from the connection of said auxiliary receiver to said transfer conduit, a second motor valve in said transfer conduit downstream from the connection of said auxiliary receiver to said transfer conduit, means for actuating said first and second motor valves to open and close alternately and in sequence, and means connected to the other side of said receiver for displacing the sealing liquid introduced thereto from said sample container into said collector vessel.

2. A system according to claim 1, in which said means for displacing the sealing liquid into said collector vessel comprises a body of mercury contained by said auxiliary receiver, a manometer tube having one end connected to the bottom of said receiver and adapted to receive said mercury when the latter is displaced by sealing liquid, said tube being vented to the atmosphere at its other end, and a means in said tube for limiting the volume of mercury displaceable into said tube.
